UNITED STATES PATENT OFFICE.

CHARLES F. KUEHNE AND PATRICK DONAHER, OF OAKLAND, CALIFORNIA.

BRAKE-STAFF.

1,308,363.

Specification of Letters Patent.

Patented July 1, 1919.

Application filed May 1, 1916. Serial No. 94,663.

To all whom it may concern:

Be it known that we, CHARLES F. KUEHNE and PATRICK DONAHER, citizens of the United States, residing at Oakland, in the county of Alameda and State of California, respectively, have invented certain new and useful Improvements in Brake-Staffs, of which the following is a specification.

This invention relates to improvements in brake operating means and has for its object the construction of an improved device of this character to be used on flat cars.

Another object of our invention is to provide a device which is attached to the corner of the car in such a manner that complies with the requirements of the Interstate Commerce Commission, that it is safe in operation, that it is out of the way in case a flat car is used in construction work or in case several flat cars are used together with long pieces of material running from one car to the other.

With these and other objects in view our invention consists in the novel construction, combination and arrangement of parts herein illustrated and more specifically pointed out in the appended claims.

Reference being had to the accompanying drawing forming a part of this specification, Figure 1 is a view in side elevation of our improved device showing the same attached to a fragmentary portion of the car body.

Fig. 2 is a view in side elevation at right angles to Fig. 1 and looking at the end of a car to which the device is attached.

Fig. 3 is a view in plan of the device and a corner of the car to which the same is attached.

Fig. 4 is a bottom view of the handle mechanism for operating the brakes.

Fig. 5 is a view in longitudinal section through one side of the handle operating mechanism.

Fig. 6 is a fragmentary view in end elevation of the member wherein the holding pawl is pivotally mounted.

Referring to corresponding parts in the several views by the same numerals of reference, 1 denotes a portion of the flat car, to one corner of which is attached the bracket 2 which consists of the hollow rectangular portion having the side walls 3 and 4, the latter being adapted to lie close to the end of the car body.

Extending from the side walls 4 are arms 5 and 6, the former being provided to en-

able the member 2 to be bolted to the car body. The side wall 4 is provided with a continuation 7 forming an arm at right angles to 5 whereby the device is fastened to the end surface of the car by a bolt at right angles to that of arm 5. Formed between the walls 3 and 4 are cross members 8, 9 and 10, having holes in which is pivotally mounted the brake staff 11.

This staff is provided with a reduced portion 12', which is pivotally mounted in the opening through the bottom connecting members, and above which is a slightly enlarged sleeve 11 pivotally mounted in member 9. Above the connecting member 10 a face ratchet 12 is attached to the said staff, this ratchet having teeth on the underside and is spaced a sufficient distance above the top surface of member 10 to enable a pawl to operate. Bracket 6 is provided with the horizontal shelf 13 wherein is slidably mounted member 38 held therein by means of bolt 15. The shelf is provided with a recess having the angular sides 39 and the lugs 14 are mounted upon base 38 which is similarly shaped whereby if the lugs become broken they may readily be replaced.

Pivotally mounted between the lugs 14 is a pawl mechanism 16 having the finger 17 adapted to engage the teeth 12 on one end and having the other end engaging a counterweight 20. This counterweight is pivotally mounted in the ears 14 above the pawl and rests loosely upon the rear end of the latter.

It will be noted that the surface of shelf 13 is below the level of the car floor but that the counter weight 20, which also serves as a foot lever, is slightly above the floor, thereby enabling the operator who is standing on the floor, by a spring-like pressure on the weight 20, to easily release the brake. A chain or other flexible cable 21 is attached to the lower end of the brake staff and passes therefrom to the brake operating mechanism.

To the upper end of the brake staff is attached the operating handle, denoted in general by 25. This handle consists of the ratchet member 26 having teeth 27 and a squared central opening 28 by which it is held in fixed relation to a similarly shaped portion on the upper end of the brake staff. A nut 30 is in engagement with the upper end of the brake staff whereby the ratchet member is held in place.

Pivotally mounted on this ratchet mem-

ber is the revoluble sleeve 31 having an extension 32 wherein is pivotally mounted the handle 33, this handle being provided with an outwardly extending finger 34, which 5 engages a corresponding shoulder in member 32, thereby preventing the handle from being raised above a horizontal position, but at the same time allowing the same to fall by gravity to a vertical position, the handle 10 being pivotally mounted on the bolt 35. Slidably mounted in a suitable opening in the sleeve 31 is a pawl 36, this pawl being controlled by a spring 37.

In use the device is attached to the corner 15 of a flat car as shown in the drawings. When it is desired to apply the brake the handle 33 is raised as far as permitted by the finger 34 and then either by a ratchet action or by complete revolution the staff 20 11 is turned to wind the chain 21 thereon. During this operation the pawl 17 engages the teeth of the ratchet wheel 12 thereby holding the chain in a state of tension. As 25 soon as the operator has ceased using the handle the same falls to a position shown in dotted lines in Fig. 2, whereby when at the most unfavorable position the extension 32 will not project beyond the limits of the car.

30 While we have shown and described the preferred embodiment of our invention it will be understood that minor changes may be made in detail and design without departing from the scope of the claims.

35 What we claim as new and wish to cover by Letters Patent is:—

1. A brake operating device comprising in

combination a box-like member, arms on said member at right angles to each other adapted to be attached to the side and end 40 of a flat car, a brake-staff pivotally mounted in said member, a ratchet carried by said staff, lugs removably attached to said member, a pawl pivotally mounted in said lugs and an operating handle secured to said 45 brake-staff.

2. A brake operating device for flat cars comprising in combination a box-like member secured to the corner of the flat car, a 50 brake-staff pivotally mounted in said member, a ratchet secured to said staff, intermediate the ends thereof, a pawl, lugs removably attached to said box-like member, said pawl pivotally mounted between said lugs, a ratchet mounted on the upper end of said staff, a sleeve surrounding said ratchet, a 55 pawl in said sleeve and a folding handle pivotally attached to said sleeve.

3. A brake of the character described comprising a member having arms shaped to be attached to the corner of a car, a brake staff rotatably mounted in said member, a ratchet secured to said staff, lugs removably secured to one of said arms, a pawl pivotally supported by said lugs and positioned to engage said ratchet, a weight pivotally supported by said lugs and positioned to engage said pawl, and means whereby the brake staff may be rotated.

70 In testimony whereof we affix our signatures.

CHARLES F. KUEHNE,
PATRICK DONAHER.
